To all whom it may concern:

Be it known that I, Louis Poglein, a citizen of the United States, residing at Jeannette, in the county of Westmoreland and State of Pennsylvania, have invented a new, original, and ornamental Design for a Bottle, of which the following is a specification, reference being had to the accompanying drawing, forming part thereof, in which Fig. 1 is a front elevational view; and Fig. 2 is a side elevational view partially in section of a bottle, showing my new design.

The characterizing features of my design reside in the glass bottle having flat sides and having an offset neck portion of substantially the width of the greatest transverse dimension of the bottle, specifically as shown.

I claim:

The ornamental design for a bottle, as shown and described.
